SEWING MACHINE

Nerino Marforio, Milan, Italy, assignor to S.p.A.
Virginio Rimoldi & C., Milan, Italy

Filed Aug. 2, 1971, Ser. No. 168,513

Claims priority, application Italy Feb. 11, 1971

Term of patent 14 years

Int. Cl. D15—06

U.S. Cl. D70—1

FIG.1

FIG.2

FIG.3

FIG.4

FIG.5

FIG.6

FIG. 1 is a front perspective view of a sewing machine showing my new design;

FIG. 2 is a top plan view thereof;

FIG. 3 is a front elevational view;

FIG. 4 is a side elevational view;

FIG. 5 is a rear elevational view; and

FIG. 6 is a side elevational view of the side opposite that shown in FIG. 4.

I claim:

The ornamental design for a sewing machine, substantially as shown and described.
